UNITED STATES PATENT OFFICE.

MORRIS SILBERSTEIN, OF NEW YORK, N. Y.

SUSPENDER-END.

SPECIFICATION forming part of Letters Patent No. 276,909, dated May 1, 1883.

Application filed December 21, 1882. (Model.)

To all whom it may concern:

Be it known that I, MORRIS SILBERSTEIN, a citizen of the United States, residing at New York, in the county and State of New York, have invented new and useful Improvements in Suspender-Ends, of which the following is a specification.

This invention relates to improvements in the braided suspender-end for which Letters Patent were issued to me August 31, 1880, No. 231,856; and the object of my present invention is to provide a braided suspender-end with a separately-constructed and attached button-hole loop or ring of like material, and also with a strengthening flat strip, which is inclosed by the braid for retaining the latter in its original, attractive, and neat form. This I accomplish in the manner and by the means hereinafter described and claimed, and 20 illustrated in the accompanying drawings, in which—

Figure 1 is a side view. Fig. 2 is a longitudinal section in the plane $\alpha\alpha$, Fig. 1. Fig. 3 is a side view in section.

25 Similar letters indicate corresponding parts.

The letter A designates the flat strip, which is made of paper, leather, buckram, or any other suitable flexible material. It is advantageous to have the material of this strip 30 possess a slight degree of rigidity or stiffness, as this enables the suspender-end to keep its form.

The letter B indicates the tubular braid.

C is a ring or loop, which may be made of 35 twine, worsted, cotton, silk, or any suitable material of a tasty appearance. The braid B may also be made of twine, worsted, cotton, or silk, or similar suitable material, and the ring C and braid B will match as regards color 40 and general appearance, so that the two will add to the pleasing appearance of the entire suspender. The ring or loop C is attached to the lower extremity of the suspender-end by sewing. The stitches are caused to pass 45 through the braid B and strip A, so as to get the advantage of the combined strength of the two and prevent the liability of tearing or pulling out.

To conceal the stitches connecting the ring 50 or loop C to the suspender-end, a band, D, is attached about the lower extremity of said

end, which covers up said stitches. This band D may be either of textile material sewed about said suspender-end, or it may be of thin sheet metal clinched about said suspender-end, or any other suitable flexible material of a pleasing appearance may be employed for this purpose. 55

To connect the suspender-end to the buckle-connection F, said end is sewed or clinched 60 between the ends of a loop or attaching-piece, E, made of leather or other suitable material.

I am aware that round cords have been inclosed in tubular braids, and I do not intend to claim such here, as my object is to have the 65 inclosed strip within the tubular braid flat and somewhat wide, so as to give the end an agreeable appearance, and also because a flat strip lies smoothly along the garments of the wearer and causes no inconvenience. 70

The tubular braid B may be formed or braided about the flat strip A by machinery, thus enabling the end to be formed rapidly and cheaply, and avoiding any sewing or stitching in this part of the operation, while 75 the braid can at the same time be formed closely about said strip A.

I do not wish to be understood as broadly claiming a suspender-end having button-hole loops separately constructed and afterward 80 attached, nor as claiming a braided suspender-end inclosing a cord, as in my patent before alluded to.

What I claim as new, and desire to secure by Letters Patent, is— 85

1. As an improved article of manufacture, a suspender-end composed of a tubular braid, B, a flat strip, A, inclosed within the braid, and of a material which is flexible, but sufficiently rigid to retain the braid in its original 90 shape and prevent stretching, and a button-hole loop or ring, C, attached by a connection which passes through the end of the braid and also through the flat strip, substantially as described. 95

2. The combination, in a suspender-end, of the tubular braid B, the flexible flat strip A, inclosed therein, and the button-loop C, separately constructed and attached by a connection which passes through both the braid and 100 its inclosed sustaining-strip, substantially as described.

3. The combination, in a suspender-end of the tubular braid B, the flexible flat strip A, inclosed therein, and the button-hole loop C, separately constructed and attached by stitches 5 passing through both the tubular braid and its inclosed sustaining-strip, substantially as described.

In testimony whereof I have hereunto set my hand and seal in the presence of two subscribing witnesses.

MORRIS SILBERSTEIN. [L. S.]
